LOADING APPARATUS

Elmer K. Hansen, Edgewood, Pa., assignor to
Westinghouse Electric & Manufacturing Com-
pany, East Pittsburgh, Pa., a corporation of
Pennsylvania

Application April 5, 1943, Serial No. 481,823

6 Claims. (Cl. 214—29)

My invention relates to loading-apparatus of a type comprising a loading-pan and a stripper-plate or member cooperating therewith so that the material on the pan may be scraped off onto or into a device to be charged or loaded. While my invention is of broad application, it has particular relation to apparatus for charging a furnace of the belt-conveyor type, in which it is desired to deposit the material on an endless belt which is continuously moving within the furnace. Such furnaces, and chargers therefor, are utilized in the heat-treatment of metal and other parts, such as iron gun-parts, cartridge-shells, screws, or washers, which require to be heat-treated in a furnace having a special atmosphere, so that it is extremely desirable for the furnace-charging operation to be performed in a very small moment of time, so that the furnace-door need be kept open only a short time, thus minimizing the loss or contamination of the atmosphere within the furnace.

Heretofore, difficulty has been encountered with such loading-apparatus, particularly because of the warping of the bottom of the loading pan, as a result of undergoing repeated cycles of heating and cooling, in charging a furnace. My invention relates to the various means for overcoming this difficulty.

A preferred form of embodiment of my invention is shown, by way of illustration, in the drawing, wherein:

Fig. 1 is a diagrammatic elevation, partly in section, showing my loading-apparatus in position relative to a furnace;

Fig. 2 is an enlarged cross-sectional view of the loading-pan, on the section-plane indicated by the line II—II in Fig. 1; and

Fig. 3 is a cross-sectional view through the scraper-member, on the section-plane indicated by the line III—III in Fig. 2.

My loading-apparatus is illustrated as comprising a carriage or other supporting-member 4, which is movable forwardly and backwardly on a track 6. The carriage or movable supporting-member 4 has two forwardly projecting side-arms 8 which, in turn, are provided with a U-bent bottom flange 9 (Fig. 2), providing a track for movably supporting a loading-pan 10, which is thus movable forwardly and backwardly with reference to the side-arms 8 of the carriage 4. The rear end of the loading-pan 10 is provided with a long handle 12, which is drawn back by means of a spring 14. A catch or latch-member 16 is provided for holding the pan 10 in its cocked or forward position, so that a depression of the

latch-member will result in a rapid jerking-back of the pan under the action of the spring 14.

The carriage 4 is disposed, on its track 6, in an operative position with respect to the door 20 of a furnace 21, which may be of the belt-conveyor type, as indicated by the endless belt 22, so that the door 20 may be momentarily opened, and the carriage 4 may be quickly rolled forward so that its forwardly projecting arms 8 extend into the furnace, with the pan 10 over the belt 22, after which the latch-member 16 may be instantly tripped, jerking back the pan 10, and depositing its charge 24 on the belt, and finally, the carriage 4 can be rolled back again, and the furnace-door 20 closed, all in the space of a few seconds time.

In accordance with my present invention, I preferably minimize warping of the pan 10 by building its bottom-member with crisscrossed warping-resisting members, preferably in the form of two metal corrugated members 30 and 31, having crisscrossed corrugations joined together, as by welding, at some or all of the touching-points 32 of the corrugations. The corrugations of the upper corrugated member 30 are disposed in a forwardly and backwardly extending direction, substantially parallel to the direction of movement of the loading-pan, while the corrugations of the lower corrugated member 31 are disposed transversely, so as to resist warping in the transverse direction.

In accordance with my invention, I also provide an improved form of scraper-member 33 which is affixed to the forwardly projecting side-arms 8 of the carriage 4, in a position to scrape off the material 24 which is carried by the loading-pan when the loading-pan is jerked backwardly by the spring 14, upon the release of the catch 16. The quick backward jerking of the pan tends to jerk the pan from under its charge 24, permitting said charge to be dropped onto the conveyor-belt 22 within the furnace, and the scraper-member 33 serves to scrape off any small pieces which may tend to cling to the bottom of the pan 10.

In my preferred, or improved, form of scraper-member 33, a movable metal scraper-plate 34 is preferably carried by a stationary scraper-frame 35 which is carried by the side-arms 8 of the carriage. The scraper-plate 34 is movable in an up-and-down direction, so that the bottom edge 50 of the scraper-plate bears against the bottom of the loading pan 10. Any suitable means may be utilized for pressing the lower edge of the scraper-plate 34 against the bottom of the pan, the illustrated means, for this purpose, being gravity, which is aided, in the illustrated embodiment, by

a special weight-member 36 which is secured to the scraper-plate 34. The movable scraper-assembly 34—36 is loosely guided, in the illustrated form of embodiment, between blocks 37, which are held between front and back plates 38 and 39 of the scraper-frame 35, by means of bolts 40, the loose play being sufficient so that the movable scraper-plate 34 is laterally tiltable, or loose, in an amount sufficient to accommodate its lower edge to any warping or unevenness in the bottom of the loading-pan 10, while the latter is being moved backwardly under the impetus of the spring 14. The bottom edge of the scraper-plate 34 is shaped, of course, to accommodate the top surface of the bottom of the loading-pan 10, that is, to accommodate the corrugations of the upper corrugated member 30.

In accordance with my invention, I also preferably subdivide the scraper-plate 34 into a plurality of individual scrapers 34A, 34B, 34C etc., each of the individual scrapers having a width considerably less than the width of the loading-pan 10, the plurality of individual scrapers being so disposed that substantially the entire material-supporting bottom of the loading-pan is collectively scraped by the plurality of scrapers. Preferably, the plurality of individual scrapers are aligned, end-to-end, in close, but spaced relation to each other, as indicated by the close spacing 42 in Fig. 2, so that the individual scrapers have a very slight amount of tiltness in the lateral direction, with respect to each other, so as to enable them to individually accommodate themselves to any slight roughness or warping of the corrugated pan-bottom on which the scrapers are resting.

In operation, experience has proved that the crisscrossed bottom-construction of the loading-pan 10 constitutes a very effective warp-resisting construction; and that the vertical movement and loose mounting of the scraper-plate, together with the subdivision of the scraper-member into a number of individual scraping-elements of relatively small width, constitutes a very effective means for scraping off even the thinnest of paper-thin objects from the bottom of the tray 10.

While I have illustrated my invention in a single form of embodiment, which at present is the preferred form, it will be obvious that many changes may be made, in the way of substituting equivalents, adding refinements, or omitting some of the features which may not always be necessary. I desire it to be understood, therefore, that the drawing is only illustrative, and that the appended claims are to be accorded the widest construction consistent with their language.

I claim as my invention:

1. A loading-apparatus comprising a forwardly and backwardly movable supporting-member having forwardly projecting side-arms adapted to project over the place where material is to be deposited, a forwardly and backwardly movable loading-member movably supported on said side-arms, and a scraper member carried by said side-arms in a position to scrape off the material carried by said loading-member when the loading-member is moved backwardly with respect to said side-arms, said scraper-member comprising a plurality of scrapers individually bearing against the bottom of the loading-member, means for so guiding each of said scrapers that it is individually movable in an up-and-down direction and each individually laterally tiltable in an amount

sufficient to accommodate the bottoms of the individual scrapers to any unevenness in the bottom of the loading-member while the latter is being moved backwardly, each of the individual scrapers having a width considerably less than the width of the loading-member, and the scrapers being so disposed that substantially the entire material-supporting bottom of the loading-member is collectively scraped by the plurality of scrapers.

2. A loading-apparatus adapted to operate under such repeated cycles of heating and cooling that warping is a difficulty, comprising a forwardly and backwardly movable supporting-member having forwardly projecting side-arms adapted to project over the place where material is to be deposited, a forwardly and backwardly movable loading-member movably supported on said side-arms, the bottom of said loading-member having crisscrossed warp-resisting members so disposed that the top surface of said bottom has forwardly and backwardly disposed elevated-portions thereon substantially parallel to the direction of movement of said loading-member, and a scraper-member carried by said side-arms in a position to scrape off the material carried by said loading-member when the loading-member is moved backwardly with respect to said side-arms, said scraper-member comprising a plurality of scrapers individually bearing against the bottom of the loading-member, means for so guiding each of said scrapers that it is individually movable in an up-and-down direction and each individually laterally tiltable in an amount sufficient to accommodate the bottoms of the individual scrapers to any unevenness in the bottom of the loading-member while the latter is being moved backwardly, the bottoms of the scrapers being shaped to accommodate the top surface of the bottom of said loading-member, each of the individual scrapers having a width considerably less than the width of the loading-member, and the scrapers being so disposed that substantially the entire material-supporting bottom of the loading-member is collectively scraped by the plurality of scrapers.

3. A loading-apparatus adapted to operate under such repeated cycles of heating and cooling that warping is a difficulty, comprising a forwardly and backwardly movable supporting-member having forwardly projecting side-arms adapted to project over the place where material is to be deposited, a forwardly and backwardly movable loading-member movably supported on said side-arms, the bottom of said loading-member being composed of at least two corrugated members having crisscrossed corrugations joined together at numerous points, the corrugations of the upper corrugated member being disposed in a forwardly and backwardly extending direction substantially parallel to the direction of movement of said loading-member, and a scraper-member carried by said side-arms in a position to scrape off the material carried by said loading-member when the loading-member is moved backwardly with respect to said side-arms, said scraper-member comprising a plurality of scrapers individually bearing against the bottom of the loading-member, means for so guiding each of said scrapers that it is individually movable in an up-and-down direction and each individually laterally tiltable in an amount sufficient to accommodate the bottoms of the individual scrapers to any unevenness in the bot-

tom of the loading-member while the latter is being moved backwardly, the bottoms of the scrapers being shaped to accommodate the top surface of the bottom of said loading-member, each of the individual scrapers having a width considerably less than the width of the loading-member, and the scrapers being so disposed that substantially the entire material-supporting bottom of the loading-member is collectively scraped by the plurality of scrapers.

4. The invention as defined in claim 2, characterized by the plurality of individual scrapers

being alined, end to end, in close, but spaced, relation to each other.

5. The invention as defined in claim 4, characterized by the plurality of individual scrapers being alined, end to end, in close, but spaced, relation to each other.

6. The invention as defined in claim 6, characterized by the plurality of individual scrapers being alined, end to end, in close, but spaced, relation to each other.

ELMER K. HANSEN.
